(57) **CLAIM**

The ornamental design for a “chromatography vial,” as shown and described.

DESCRIPTION

FIG. 1 is a top perspective view of a first embodiment of a chromatography vial showing my new design;

FIG. 2 is a front elevational view thereof;

FIG. 3 is a top plan view thereof;

FIG. 4 is a bottom plan view thereof;

FIG. 5 is a cross-sectional view thereof taken through the line 5—5 of FIG. 2;

FIG. 6 is a top perspective view of a second embodiment of a chromatography vial showing my new design;

FIG. 7 is a front elevational view thereof;

FIG. 8 is a top plan view thereof;

FIG. 9 is a bottom plan view thereof; and,

FIG. 10 is a cross-sectional view thereof taken through the line 10—10 of FIG. 7.
